Primary Examiner — Karen E Kearney*Assistant Examiner* — Kristin E Reed(74) *Attorney, Agent, or Firm* — Goodwin Procter LLP(57) **CLAIM**

The ornamental design for a display screen with graphical user interface, as shown and described.

DESCRIPTION

The FIGURE is a front view of a display screen with graphical user interface.

The outer dot dash broken line showing the display screen and all other broken lines showing portions of the graphical user interface are included for the purpose of illustrating environmental structure and form no part of the claimed design.

1 Claim, 1 Drawing Sheet(56)
